UNITED STATES PATENT OFFICE.

ODAVILLE YATES, OF PORTLAND, OREGON.

NON-REFILLABLE BOTTLE.

SPECIFICATION forming part of Letters Patent No. 784,199, dated March 7, 1905.

Application filed October 11, 1904. Serial No. 228,036.

To all whom it may concern:

Be it known that I, ODAVILLE YATES, a citizen of the United States, residing at Portland, in the county of Multnomah and State of Oregon, have invented new and useful Improvements in Non-Refillable Bottles, of which the following is a specification.

This invention relates to non-refillable bottles, and has for its object to provide a bottle of this character with an improved valve-controlling mechanism which will hold the valve seated and prevent discharge of the contents when the bottle is disposed in a horizontal or tilted position, it being necessary to entirely invert the bottle to dispense the liquid therein, and thus the bottle cannot be refilled.

The invention further consists in the detailed construction, combination, and operative aggroupment of the parts, all as will be more fully described hereinafter, illustrated in the accompanying drawings, and finally pointed out in the appended claims.

In the drawings, Figure 1 is a vertical section through the neck and upper end of the body of the bottle with my improved valve mechanism mounted therein. Fig. 2 is a plan view of the bottle with the valve mechanism mounted therein and with the detachable neck and guard for the valve mechanism removed. Fig. 3 is a vertical section at right angles to Fig. 1, showing the bottle tilted to an almost inverted position. Fig. 4 is a side elevation of the valve mechanism.

Making renewed reference to the drawings, 35 1 designates the body of the bottle, having its upper end formed with an integral upstanding and inwardly-directed flange 2, the edges of which are provided with diametrically-disposed recesses 3. Beneath the flange and 40 extending about one-fourth way therearound are inclined circumferential segments 4, which are indicated in dotted lines in Fig. 2. The flange 2 is surrounded by a marginal annular recess 2^a, into which the overlapping edge 10 of a detachable neck 8 fits. This detachable neck is provided with the usual bore 5, which may be closed by a stopper 6 at the upper end, and in its lower end is formed an annular chamber 7. Depending from the bottom of the de-

tachable neck and separated from the overlapping edge 10 thereof are lugs 9, that have outwardly-disposed noses 11, adapted to be inserted into the recesses 3 in the flange 2 and engaged beneath the inclined segments 4. When the neck is attached and given a partial rotation, the upper edges of the noses of the lugs engage with the inclined surface of the segments 4 and bind the neck down with the overlapping edge 10 into intimate contact with the annular recess 2^a, and, if desired, any suitable cement or plastic material may be previously inserted in the annular space 12, which is surrounded by the flange 2, and of course when this cement hardens it offers an obstruction to the lugs 9 and prevents removal of the neck. 55

The upper end of the body portion of the bottle is further provided with a vertically-disposed flange 13, arranged concentric to the flange 2 and forming the inner wall of the annular space or chamber 12. This vertical 70 flange extends partially up into the chamber 7 in the detachable neck and supports the valve mechanism 14, which consists of a cap 15, that fits over the flange 13 and from which depends a frame 16, the lower end of which 75 is secured to a controller-casing 17. The cap 15 may be frictionally held upon the flange 13 or it may be attached by piercing the flanged end 18 with tacks or other fastenings, and its top is perforated to provide a port 19, 80 and the edges of the metal around the port are offset to provide a valve-seat 20 for the valve 21. The side pieces of the frame are braced at several points by cross-bars 22 and 23, through which the valve-stem 24 passes to 85 form guides for said stem, which is jointed at 25 and has on its lower end a weight 26. The top of the casing 17 is perforated, as at 27, so as to permit the joint of the valve-stem to 90 freely slide therethrough when the valve opens and closes. On the valve-stem, below the joint thereof, is a controller-disk 28, which is inclosed by the casing 17 and free to oscillate and reciprocate therein when the weighted end of the valve-stem is tilted out of alignment with the stationary portion thereof, as 95 will be further explained in the statement of the operation.

An annular sheath 30 extends from the top of the cap 15 and incloses the valve, which is covered by a guard 31, supported from opposite edges of the sheath, as at 32, the guard 5 and sheath being located well up into the chamber 7 of the detachable neck.

When the bottle has been filled, the valve mechanism 14 is positioned in place by inserting the cap 15 over the flange 13, and the detachable neck is then applied, as before stated. The weight 26 on the end of the valve-stem will normally hold the valve seated and prevent the further introduction of liquid into the bottle; but by entirely inverting the bottle the weight will force the valve from its seat and the liquid will then pass through the space between the top of the casing 17 and the bottom of the flange 13 and into the space occupied by the frame, through the port 19, 15 around the guard, and out of the neck, as indicated by the arrows. However, the peculiar construction of the parts associated with the valve and its casing is such as to prevent the former from being unseated unless the bottle is 20 entirely inverted, in which position it would be impossible to refill the bottle, inasmuch as access cannot be had to the valve by an instrument on account of the guard, and any force sufficient to inject a liquid into the bottle in this 25 inverted position would also be sufficient to close the valve, which would then act as a check-valve, and, furthermore, such operation would be attended with more or less inconvenience in view of the air in the bottle and the back pressure of the liquid through the 30 port, which is only open when the bottle is inverted. From Fig. 3 it will be seen that when the bottle is tilted either to a horizontal position or to a position at an acute angle with 35 the true horizontal the weight 26 will cause the valve-stem to break joint, and the controller-disk, which is rigid on said stem, will act as a fulcrum in the casing 17, the fulcrum-point being at one side of the joint in the 40 valve-stem, and thereby causing a direct pull on the valve-stem, which will hold the valve seated until the center of gravity is overcome 45 by entirely inverting the bottle.

Having thus described my invention, what

I claim, and desire to secure by Letters Pat- 50 ent, is—

1. In a non-refillable bottle, a body provided with an upstanding flange, a cap fitting over said flange and having a valve-seat in the top thereof, a frame depending from said cap, a 55 casing secured to the lower end of said frame, a valve to close the seat, a jointed valve-stem piercing the said frame and the casing with the joint thereof adjacent to the top of said casing, a weight on the lower end of the valve-stem, 60 and a controller-disk on the valve-stem below the joint thereof and loosely confined within said casing, whereby the edge of said disk acts as a fulcrum within the casing to exert a pull upon the valve-stem when the bottle is tilted. 65

2. In a bottle of the class described, the combination of a body portion having an upstanding inwardly-directed annular flange provided with inclined segments, a detachable neck having depending lugs to engage the inclined face 70 of said segments and also having an annular chamber in the lower end thereof, a vertical flange on the top of the body portion projecting partially within the chamber of the neck, a valve mechanism having a cap fitted over said 75 last-mentioned flange and provided with a valve-seat in its top, an annular sheath projecting from the top of said cap and inclosing the valve, a guard above said sheath, a frame depending from said cap, a casing secured to the 80 lower end of said frame, a valve normally held seated on the top of said cap, a jointed valve-stem projecting through the frame and casing, a weight on the lower jointed end of the valve- 85 stem, and a controller-disk secured to the valve- stem below the joint thereof and adapted to have a fulcrum within the casing when the weight falls to one side by the tilting of the bottle, whereby the valve will be held seated when the bottle is tilted, substantially as speci- 90 fied.

In testimony whereof I affix my signature in presence of two subscribing witnesses.

ODAVILLE YATES.
